UNITED STATES PATENT OFFICE.

ARTHUR STOCKSTROM, OF ST. LOUIS, MISSOURI, ASSIGNOR TO AMERICAN STOVE COMPANY, OF ST. LOUIS, MISSOURI, A CORPORATION OF NEW JERSEY.

GAS RANGE AND BURNER THEREFOR.

Application filed October 4, 1926. Serial No. 139,400.

This invention relates to improvements in gas ranges and burners therefor, the particular features being pointed out hereinafter.

One of the features of the present invention is substantially closing that part of the range containing the open burners, sufficient space being provided in its sides and bottom for the passage of air for the burners, the burner top being substantially closed with the exception of the grids for supporting the cooking utensils.

Another feature of the invention is making a particular kind of burner which is small as compared with the grids for supporting the cooking utensils and at the same time so constructing the burner that the flame spreads under the utensil, the top above the burners being substantially closed but at the same time provided with openings sufficient to accommodate the flame from the burners.

A further feature of the present invention is making a burner much smaller in circumference than the grid on which the utensil is placed, causing the utensil to form a protection to the burner below from overflow of what may be cooking.

Another feature of the present improvement is providing burners formed very much smaller in circumference than the open grids above, and so constructing the burner that the flame is caused to spread over a surface as great and possibly greater than the surface of the grid portion.

A further feature of the present improvement is to provide a central manifold to which the four burners are connected, and from which the separate manifolds of the burners extend in opposite parallel directions, whereby the said burners are properly located at the usual four corners of the burner top.

Another feature of the present invention is providing supports for the free ends of the burner manifolds, or the bottom of the burners themselves, whereby the said burners are supported in proper position and are readily removed and replaced.

Another feature of the present invention

is combining with the burners as above stated and said supports, certain members carried by the manifolds of the burners or the lower ends of the burners themselves whereby the burners cannot be placed in their wrong positions, thus insuring at all times that the parts are properly assembled.

Further features of the present invention will appear from the following description.

Referring now to the accompanying drawings in which:

Figure 1 is a perspective view of a stove which embodies the present invention.

Figure 2 is a top plan view of the stove.

Figure 3 is a horizontal section through Figure 1 just below the top portion.

Figure 4 is a vertical sectional view on the line 4-4 of Figure 3.

Figure 5 is a vertical sectional view on the line 5-5 of Figure 2.

Figure 6 is a view of the burner and its support, the same being shown in disconnected relation.

Figure 7 is an enlarged view partly in vertical section through one of the burners and its manifold.

Referring now to the drawings, 1 represents the oven of the range to one side of which is supported the open burner construction that will be now explained.

This open burner construction in carrying out the present improvement, consists of a rectangular arrangement comprising a front 2, an end 3, a back 4 and an oven portion 5, all of which are vertically disposed. In addition to the above is the top, which in this instance preferably is comprised of two top members 6, which top members are also substantially closed with the exception of the grid portions 8, and relatively smaller openings 9 located at the edge of said grids. The particular construction of this top will be described hereinafter.

In carrying out the above described closed construction and the necessary cooperating parts, attention is called to a centrally arranged gas manifold 10, that is connected with a fuel supply 11 that passes through the rear wall 12 to a source of supply which

is not here illustrated. The burner manifolds 13 have their lower shutter ends 14 extending down and loosely fitting around nozzles 15 that extend from the gas manifold 10, while projecting vertically from the upper ends of these manifolds are the burners 16 the whole structure provides a Z-shaped member.

By referring to Figure 2, the relative size 10 of the burners 16 compared with the grids 8, is clearly shown. From this it will be readily realized how the burners are substantially completely protected from overflowing cooking by the utensil itself which 15 is always substantially as large as the grid 8.

The supply of gas from the central manifold 10 to the respective burners is controlled by suitable handles 17 that are connected by a suitable rod 18 with the valve control 19. 20 The stove is preferably provided with a pilot 20 which is controlled by a handle 21 extending through the front 2 which will send out flames for lighting the respective burners. The type of pilot is well understood and need not be further described or 25 illustrated.

We have heretofore referred to the fact that the burner manifolds and burners are detachable from the central manifold 10, 30 which will now be specifically explained. In placing these burners in position, the member 21 which extends from the lower end of the burner 16, or may extend from the manifold itself, is passed through an opening 35 22, made in a support 23 that extends across between the walls 3 and 5 with its ends connected thereto. This support 23 has in addition to the opening 22, a lateral opening 24 which is adapted to receive the projection 25 40 located on the lower side of the member 21, and the member 21 has a horizontally extending projection 25, the purpose of which will be presently explained.

In assembling the burners the member 21 45 and projection 24 are passed through the openings 22 and 24', after which the shutter part 4 is placed on its nipple and the angle of the manifold 13 is regulated by the projection 25 substantially engaging its support 50 23. In detaching the burners from the stove, the shutter end thereof is lifted when the member 21 can be readily withdrawn from its support. In this manner 55 burners and manifold are readily assembled and detached and their proper relative positions are at all times insured, the construction being such that the parts cannot be assembled in their wrong relative positions. When they are assembled, two of the manifolds 60 and the burners extend in one direction and the other two in another direction, while they all extend in parallel horizontal planes as well as vertical planes. This insures that the burners will occupy the usual corner positions of the top 6.

At this point we will refer to the particular construction of the burner 16. This burner is covered per se in an application filed by the present inventor on August 30, 1926, Serial No. 132,534, but a burner constructed as disclosed in the application has a special function in connection with the top 6 as will now be explained. Hereinbefore it has been stated that these burners are very much smaller than the gird 8 which 70 is one feature of this special burner in connection with this top, it having the advantage hereinbefore referred to. This burner has its outer wall provided with openings 26 that extend outwardly with openings 27 that 75 extend upwardly and inwardly at an angle. By reason of this construction a burner much smaller than the gird produces a flame that completely covers the bottom of the utensil above, the flame spreading and also being 80 concentrated on the bottom of the utensil and insures that its contents will be heated substantially alike throughout its entire bottom, while at the same time the openings 9 around the grids 8 provide passages for this 85 enlarged flame so that the flame will cover the complete bottom of the utensil that is 90 larger in diameter than the diameter of the grid 8.

My new top 8 is made preferably in two 95 like parts being divided at its center 28 for convenience in the handling of the same. The construction of this has been described in respect to the grids and the openings in it, and in addition particular attention is called 100 to the ribs 29 which are elevated and arranged so that the utensils may be readily moved around on the top, and at the same time so that they will be above the top. For instance when the utensil is over the grid, 105 then there is a space between it and the top for the passage of the flame from the burner, whereas the utensil can be readily moved laterally on the top to any desired position. There is preferably provided one or more 110 solid grid portions 30 which may be used if desired, and these are particularly adapted for small articles. When a small utensil is being heated, for instance a cup of any kind, this solid part 30 will protect the 115 burner below from the overflow from the utensil and at the same time it will provide a solid heating surface. As to the ridges on this top 8, attention is directed to the fact that the said ridges that connect with the grid portions are made angular in formation, while the other ridges 31 extend radially to the grids. 120

The bottom of the rectangular portion comprising the walls 2, 3, 4 and 5 is provided with a dirt slide 32 which is capable of being removed for the purpose of cleaning it. This dirt slide will naturally receive part of the overflowing material, that part remaining on the top also being readily re- 125 130

5 moved. This dirt slide 32 substantially closes the bottom of the structure, there being left, however, room around it so that air will flow to the burners, as well as flow through the openings 33 in the walls 3 and 4. These openings together with the portions, serve to substantially enclose the burners and the main manifold whereby they are all out of sight, thus producing a very popular 10 structure.

15 While I have described in detail the present invention, I wish it understood that variations may be made in the construction shown and described without departing from the scope and spirit of the present invention, so long as the said variations will come within a fair interpretation of the appended 20 claims.

Having thus described my invention, what 25 I desire to claim and secure by Letters Patent is:

1. A gas stove, burners located within and below the top, said top having grid portions with openings around the said grids, the 25 burners provided with inwardly and outwardly inclined openings whereby a relatively enlarged flame is provided to fill the said grid openings and the openings of the top around said grids.

30 2. A gas stove having a manifold extending substantially through the center thereof and below its top, L-shaped burner manifolds having at their upper ends vertically extending burners and at their lower ends a shutter portion cooperating with the central manifold, said burner manifolds extending outward in opposite directions from said central manifold, the said burners being located under the four corners of the top 40 portion.

35 3. A gas stove having vertical walls which are substantially closed and the top wall of which is substantially closed, excepting grid openings, a manifold passing through the said stove in substantially its central portion, L-shaped manifolds having at their upper ends burners and at their lower ends shutter portions cooperating with the said manifold to receive the fuel, said burners extending outwardly in opposite directions and in angular relation to the said central manifold, the said burners being located substantially under the four corners of the top.

45 4. A gas stove having substantially closed vertical side portions, a top portion substantially closed excepting the grid portions, burners located under the grid portions, said burners having L-shaped manifolds cooperat- 50 ing with a centrally arranged manifold within said closure, and handles located outside of and passing through the vertical wall and extending to the central manifold for controlling the flow of gas to the said burn- 55 ers.

5. An improved gas stove structure having a substantially closed housing with vertical closed walls, a manifold passing longitudinally and substantially through the center of the housing, a plurality of separated 70 burners operatively connected with the said manifold, gas valves located between said burners and the manifold and separate handles located outside of one vertical wall passing therethrough and operatively connected with the said valves for the purpose of controlling the flow of fuel from the outside of the closure. 75

6. An improved gas range structure having a substantially closed housing, a longitudinally and centrally arranged manifold within the said housing, a plurality of separate burners having separate L shaped manifolds, the vertical leg of the L operatively connected with the said manifolds and their 80 opposite ends provided with vertical burners, said separate manifolds extending outward in opposite directions, supports located within said housing between the separate burners and said vertical walls, said burners provided with outwardly extending projections loosely interlocking with the said supports, whereby the burners are readily removed or supported within the said closure. 85

7. An improved gas stove comprising a 90 substantially closed housing, a longitudinally arranged manifold centrally passing through the said housing, separate burners having L-shaped manifolds, the inner ends of the manifolds being vertical and operatively connected with the centrally arranged manifold, the opposite end of the burner manifolds carrying vertical burners, said burners and manifolds arranged to extend outwardly in 95 opposite directions in substantially parallel planes at an obtuse angle to the said manifold, and supports within the housing located between the burners and the burner walls of the housing, the burners carrying 100 members projecting outwardly in opposite directions and loosely engaging the supporting members for the purpose described. 105

8. An improved gas stove having a substantially closed housing, a main manifold passing longitudinally and substantially centrally through the said housing, separate manifolds having their inner ends connected with the main manifold and carrying 110 burners at their outer ends, supports within the housing located at one side of said manifold and having substantially horizontally elongated slots, the burners having each horizontally elongated projections adapted to enter the slots, said projections provided at 115 their inner ends with a horizontally extending projection cooperating with the support for positioning the burners and their manifolds within the said housing. 120

9. An improved gas stove comprising a 130 substantially closed burner housing having

a main manifold extending longitudinally and substantially centrally through the housing, separated oppositely extending Z-shaped sub-manifolds with their inner ends connected operatively with the main manifold, their outer ends provided with burners, separate supports for the outer ends of the burners located at one side of said main manifold, the said supports and the burners provided with loosely interlocking members to properly position them within the said housing.

10. An improved gas stove comprising a substantially closed burner housing, a main manifold passing longitudinally and substantially centrally through the said housing, separated sub-manifolds having their inner ends operatively connected with the main manifold and their outer ends provided with 15 burners, supports for the burners located at one side of the main manifold having substantially elongated horizontal slots, said burners provided with horizontally elongated projections adapted to enter the said slots, the said slots having a lateral indentation and the underside of the burner projection provided with an extension whereby the parts cooperate to loosely support the burners within the said housing.

30. 11. An improved gas stove having a substantially closed burner housing, a main manifold passing therethrough, separate Z-shaped sub-manifolds having their inner ends operatively connected with the main manifold and carrying burners at their outer ends, separate supports for the said burners comprising projections carried by the burners and horizontal supports carried by the housing located at one side of said manifold, 35 the horizontal supports and the burner projections constructed to engage in positions out of a horizontal line with the inner ends of the sub-manifolds whereby the burners are properly positioned within the said housing.

40. 12. An improved gas stove comprising a substantially closed burner housing having a main manifold enclosed substantially in the center of the said housing, separate removable sub-burner manifolds having their inner ends operatively connected with the main manifold at different points, separate supports located at one side of said main manifold and located in a vertical plane drawn 45 between the connections of the sub-manifolds with the main manifold, and the outer ends of the sub-manifolds provided with means adapted to loosely engage said supports, whereby the burners are properly located between the said housing.

50. 13. A gas stove having substantially a rectangular portion, a main manifold extending substantially horizontally through the center thereof and below its top, separate Z-shaped

55 combined burners and manifolds, said burners forming the upwardly extending leg of the Z and the other leg of the Z extending downward and having a shutter portion cooperating with said main manifold, said burners arranged in pairs, each pair extending in opposite directions from the main manifold, said burners being substantially located under the four corners of said top portion.

14. A gas stove having substantially a rectangular closed housing, a main manifold passing substantially through the center of said housing, four combined burners and manifolds, each manifold and burner forming substantially a Z-shape, the lower end of 60 the Z cooperating with the main manifold, said burners alternately extending in opposite directions from the main manifold and in parallel angles to the main manifold, said burners being located substantially under 65 the four corners of the top.

15. An improved stove having a burner housing, a main manifold extending horizontally and substantially centrally through the said housing, a plurality of Z-shaped 70 combined burners and manifolds, the burners located at the outer ends of the manifolds and extending upwardly and the inner ends of the manifolds extending downwardly and loosely connected with the main manifold whereby the burners extend in opposite directions and may be turned substantially to the corners of the housing, and supporting means loosely supporting said burners, said burners and manifold being 75 readily removable by being lifted from their communication with the main manifold substantially as described.

16. A gas stove comprising a burner portion, said burner portion having a longitudinally extending manifold located therein between its walls, a plurality of separate burners having substantially L-shaped manifolds, the upper ends of said manifolds provided with burners and their lower ends cooperating with the said manifold and supports within the said structure located at one side of said main manifold and provided with horizontal slots loosely receiving and supporting said burners and ends of said manifolds.

17. A gas stove having a longitudinally and substantially centrally arranged manifold, an L-shaped manifold having its lower portion connected with the said manifold and its upper portion provided with a burner, a support for the burner end of the manifold, said support provided with a horizontal opening, the burner provided with a horizontally projecting member loosely engaging said opening whereby the burner and manifold are supported in proper operative position.

18. An improved gas stove comprising a substantially closed burner housing having a centrally arranged main manifold extending longitudinally through the said housing, a plurality of Z-shaped manifolds extending in opposite directions from the said main manifold, supports formed at opposite sides of the main manifold and adapted to loosely support the outer ends of the said Z-shaped manifolds for the purpose described. 10

In testimony whereof I hereunto affix my signature.

ARTHUR STOCKSTROM.
